UNITED STATES PATENT OFFICE

160,236

TEXTILE FABRIC OR SIMILAR ARTICLE

Evelyn Wintrich, Bronx, N. Y., assignor to Hess, Goldsmith & Co., Inc., New York, N. Y., a corporation of Delaware

Application December 1, 1949, Serial No. 6,358

Term of patent 3½ years

(Cl. D92—1)

To all whom it may concern:

Be it known that I, Evelyn Wintrich, a citizen of the United States and a resident of Bronx, New York, in the county of Bronx and State of New York, have invented a new, original, and ornamental Design for a Textile Fabric or Similar Article, of which the following is a specification, reference being had to the accompanying drawing, forming a part thereof, wherein the figure of the drawing is a plan view of textile fabric embodying my new design. The unit design is outlined in broken lines, and this unit is repeated over the fabric as indicated.

I claim:

The ornamental design for a textile fabric or similar article, substantially as shown.

EVELYN WINTRICH.
